R. E. Bennett, INVENTOR
BY Victor J. Evans

ATTORNEY

UNITED STATES PATENT OFFICE

ROZE E. BENNETT, OF MIAMI, FLORIDA, ASSIGNOR OF ONE-HALF TO W. H. SUTCLIFFE
AND LOUISA PARKER, BOTH OF MIAMI, FLORIDA

BRASSIÈRE

Application filed May 31, 1930. Serial No. 458,228.

This invention relates to a brassière, the general object of the invention being to provide a garment which will act as a slight support for the bust and which will act as a cover for the bust when worn with summer clothes, evening dresses, negligees, etc.

Another object of the invention is to provide means whereby the garment can be easily and quickly adjusted and one in which there is no danger of the shoulder ribbons slipping off the shoulders or getting out of place.

This invention also consists in certain other features of construction and in the combination and arrangement of the several parts, to be hereinafter fully described, illustrated in the accompanying drawings and specifically pointed out in the appended claims.

20 In describing the invention in detail, reference will be had to the accompanying drawings wherein like characters denote like or corresponding parts throughout the several views, and in which:—

25 Figure 1 is a front view of a person wearing the device.

Figure 2 is a rear view of a person wearing the device.

30 Figure 3 is an enlarged front view of the device.

Figure 4 is a section on line 4—4 of Figure 3.

Figure 5 is a section on line 5—5 of Figure 3.

35 Figure 6 is a view of the blank of material from which each part is formed.

As shown in these drawings, the device comprises a pair of triangular shaped parts 1 and 2, each part being formed of a rectangular piece of material, as shown at 3 in

40 Figure 6, which is folded on the line 4 which extends from one corner of the material to the other so that when the material is folded, it will form a triangular shaped piece. A

45 dart 5 is formed at the center of the blank so that when the material is folded on the line 4, the central part, containing the dart, will be of six thicknesses, as shown in Figures

4 and 5. The edges of the folded material

50 are stitched together, as shown at 6, and one part, so that the stresses may be properly ap-

point of each part of the garment is fastened to the other part at a point adjacent the dart, as shown at 7, so that the lower inner corners of the two parts 1 and 2 overlap each other, as shown in Figure 3. The two parts are 55 also tacked together at the point 8. A ring 9 is sewn to the base of each dart and one end of a ribbon 10 is sewn to the outer lower corner of each part. A ribbon 11 is sewn to the upper corner of each part, these ribbons 60 11 being adapted to be passed over the shoulders of the wearer and have their other ends fastened to a ring 12. The ribbons 10 are adapted to be passed through this ring 12 and then said ribbons are brought forwardly 65 around the body and passed through the rings 9, where they are tied together in a bow, as shown at 13. By suitably adjusting these ribbons 10, a strain is exerted upon the ribbons 11 so that the parts 1 and 2 are properly 70 adjusted on the wearer. The garment is not meant for a great amount of confinement of the bust, but serves to slightly support the same, as it is principally designed as a covering for the bust when low neck dresses are 75 worn. It is also useful with sport clothes, as the ribbons will not slip off the shoulders even during violent movements of the body and the garment does not compress the body anywhere and gives the body the utmost 80 freedom.

It is thought from the foregoing description that the advantages and novel features of the invention will be readily apparent.

It is to be understood that changes may be 85 made in the construction and in the combination and arrangement of the several parts, provided that such changes fall within the scope of the appended claims.

The parts 1 and 2 have been referred to in the preceding specification as being triangular shaped, however, said parts may have peripheral edges defining other shapes without departing from the spirit of the invention. 90 It is essential however, that the attaching points, at which the parts are connected with each other and the ribbons, be triangularly located with relation to each other, on each 95 100

plied when the brassière is in position upon the body of the wearer.

What I claim is:—

1. A garment of the class described comprising a pair of members having triangularly located attaching points and their inner lower portions overlapping, with the inner point of each member connected to about the center of the bottom part of the other member, ribbons connected with the lower outer points, ribbons connected to the upper points and adapted to pass over the shoulders of the wearer, the first mentioned ribbons passing around the waist of the wearer, a ring to which the rear ends of the shoulder ribbons are connected, the first mentioned ribbons passing through said ring and then brought forwardly around the body and fastened together at the front.
2. A garment of the class described comprising a pair of members having triangularly located attaching points and their inner lower portions overlapping, with the inner point of each member connected to about the center of the bottom part of the other member, ribbons connected with the lower outer points, ribbons connected to the upper points and adapted to pass over the shoulders of the wearer, the first mentioned ribbons passing around the waist of the wearer, a ring to which the rear ends of the shoulder ribbons are connected, the first mentioned ribbons passing through said ring and then brought forwardly around the body and fastened together at the front and rings connected with the central lower portions of the two members and through which the first mentioned ribbons pass.
3. A garment of the class described comprising a pair of triangular shaped members, each formed of a square of material folded on a line extending from one corner to the other, with the edges of the folded parts connected together, said square having a dart at its center and extending at right angles to the fold line, the lower inner corner of each member being connected to the central part of the lower edge of the other member whereby the inner portions of the two members overlap each other, with the intersecting edges of the two members connected together, a ring sewn to the lower edge at the center thereof of each member, ribbons connected with the outer points of the members, ribbons connected with the upper points of the members and passing over the shoulders of the wearer, means for connecting the shoulder ribbons to the side ribbons, said side ribbons passing around the waist of the wearer and through the front rings, after which they are fastened together.

In testimony whereof I affix my signature.
ROZE E. BENNETT.
